Primary Examiner — Thomas Johannes*Assistant Examiner* — Shawn T Gingrich(74) *Attorney, Agent, or Firm* — Schwabe, Williamson & Wyatt, P.C.(57) **CLAIM**

We claim the ornamental design for a bracket for display assembly, as shown and described.

DESCRIPTION

FIG. 1 is a perspective view of a bracket for display assembly, showing our new design in a position of use;

FIG. 2 is a perspective view of the bracket for display assembly;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken line portion of the figure drawings is included to show portions of the article that form no part of the claimed design.
